[57] CLAIM

The ornamental design for a digital clock housing, substantially as shown and described.

DESCRIPTION

FIG. 1 is a top, and right front perspective view of a digital clock housing showing my new design;
FIG. 2 is a top and right front perspective view thereof with the display in open position;
FIG. 4 is a right side elevational view thereof with the display in open position;
FIG. 5 is an inverted rear elevational view thereof;
FIG. 6 is a top plan view thereof, the bottom being substantially plain and unornamented except for a base (ring?);
FIG. 7 is a right side elevational view thereof, the left side being a mirror image thereto;
FIG. 8 is a front elevational view thereof.
